J. B. GILLIES.

HORSESHOE.

APPLICATION FILED OCT. 3, 1921.

1,429,583.

Patented Sept. 19, 1922.

John B. Gillies
for his wife M. Gillies
attorney.

UNITED STATES PATENT OFFICE.

JOHN BUCHANAN GILLIES, OF THORNHILL, ONTARIO, CANADA.

HORSESHOE.

Application filed October 3, 1921. Serial No. 505,017.

To all whom it may concern:

Be it known that I, JOHN BUCHANAN GILLIES, of the village of Thornhill, in the county of York, and Province of Ontario, 5 Dominion of Canada, have invented certain new and useful Improvements in Horseshoes; and I hereby declare that the following is a full, clear, and exact description of the same.

10 My invention relates to a horseshoe comprising two segmental sole plates pivotally connected together at the toe for their expansion and contraction in the fitting of the shoe to the sole of the hoof, adjusting means 15 at or near the heel of the shoe for the accurate spacing of the sole plates, and means for clamping the shoe to the hoof, the adjusting means for the sole plates being so located as to exert a pressure on the frog of the hoof 20 and maintain it in a healthy condition.

Figure 1 is a vertical plan view of the horseshoe, with the toe plate constituting the toe band shown in a practically vertical position;

25 Fig. 2 is a side elevation of the same.

The shoe consists of two segmental sole plates 1 and 2 having a pivot joint 3 at the toe by which they can swing outwards from, or inwards towards each other, in the adjustment 30 of the shoe to the sole of the hoof.

Pivotally connected to each sole plate, in the vicinity of the heel 4, are bolts 5 and 6 respectively, extending inwardly from the sole plates towards the central axis of the 35 shoe, and threaded on the bolts 5 and 6 is a turnbuckle 7 for respectively spreading or contracting the sole plates and effecting the accurate adjustment of the shoe to the sole of the hoof, the bolts and turnbuckle being 40 so located with respect to the heel of the shoe, that they will engage the frog of the hoof and maintain on it the pressure which is necessary to keep it in a healthy condition.

45 At the toe of the shoe is a toe-clip comprising a metal band 8, shaped to engage the hoof, and a pair of metal links 9 and 10 connecting the metal band with the sole plates 1 and 2 respectively.

50 In the preferred construction, the sole

plates are formed with through apertures 11 and 12 respectively and the links are formed with eyes inserted through the apertures and embracing the metal between the apertures and the perimeter of the plates to provide 55 for a turning connection of the toe-clip with the shoe, during the adjustment of the metal band to the hoof.

The metal band is formed near its extremities with bolt holes 13 and 14, and at 60 the heel of the shoe, the plates 1 and 2 are provided with through holes 15 and 16 respectively for the eyes 17 and 18 of the hoof straps 20 and 21. The insertion of the eyes of the hoof straps through these holes forms 65 a hinge connection between the hoof straps and the shoe. The hoof straps, near their free ends, are screw-threaded and these screw-threaded extremities are inserted through the holes 13 and 14. Nuts 22 are 70 threaded on the straps and engage the outer surface of the band 8. When the nuts are tightened, they bind the straps and toe-clip against the hoof and tightly clamp the shoe 75 in place.

The sole plates may be provided with holes 23 for the toe calk or calks with holes 24 for the heel calks.

In the use of the shoe, the sole plates, when the hoof is trimmed, are placed against the sole of the hoof and the turnbuckle is operated to adjust them until their perimeter is in line with the outer wall of the hoof. The nuts 22 are then tightened on the screw-threaded extremities of the shoe straps 20 80 and 21 to draw them and the band 8 tightly against the hoof and hold the sole plates 85 securely in position.

By means of this construction, the shoe can be fitted to the hoof without the employment 90 of nails or other permanent fastening devices and can be easily and quickly removed and replaced whenever it is necessary to trim the hoof or renew the shoe.

Having thus fully described my invention, 95 what I claim as new and desire to secure by Letters Patent is:

A horseshoe comprising two segmental plates pivotally connected together at the toe for their contraction and expansion, ad- 100

justing means for the accurate spacing of the sole plates consisting of a turnbuckle and bolts connected with the sole plates, and means for clamping the shoe to the hoof consisting of a toe-band shaped to engage the toe of the hoof, links pivotally connecting said band with the sole plates, and hoof straps pivotally connected at one end with the sole plates near the heel of the shoe and

adjustably connected at the other end with 10 the toe-band.

Dated at the city of Toronto, this thirteenth day of September, A. D. 1921.

JOHN BUCHANAN GILLIES.

In the presence of—

STANLEY RICHES,

ROBERT MCCLINTOCK.
